United States Patent Office

Des. 232,963
Patented Sept. 24, 1974

232,963

WATER SLED

Richard W. Turner, 1786 Tubbs St.,
Thousand Oaks, Calif. 91360

Filed July 14, 1972, Ser. No. 271,735

Term of patent 14 years

Int. Cl. D21—03; D12—13
U.S. Cl. D34—42

FIG. 1.

FIG. 2.

FIG. 3.

FIG. 4.

FIG. 5.

FIG. 6.

FIG. 7.

FIG. 8.

FIG. 9.

FIG. 10.

FIG. 11.

FIG. 12.

FIG. 13.

FIG. 1 is a perspective view of a water sled showing my new design;

FIG. 2 is a top view thereof;

FIG. 3 is a side elevational view thereof;

FIG. 4 is a bottom view thereof;

FIG. 5 is a front view thereof;

FIG. 6 is a rear view thereof;

FIG. 7 is a bottom view of a water sled showing a modified form thereof having a curvilinear bottom;

FIG. 8 is a front view of the modified design of FIG. 7;

FIG. 9 is a rear view of the modified design of FIG. 7;

FIG. 10 is a side elevational view of a water sled showing a further modified form thereof having a flat bottom;

FIG. 11 is a bottom view of the modified design of FIG. 10;

FIG. 12 is a front view of the modified design of FIGS. 10 and 11; and

FIG. 13 is a rear view of the modified design of FIGS. 10 and 11.

The side view opposite from the view of FIG. 3 is a mirror image of the view of FIG. 3.

The side views of the modified design of FIGS. 7-9 are the same as the side views of the design of FIGS. 1-6.

The side view opposite that of FIG. 10 is a mirror image of the view of FIG. 10.

I claim:

The ornamental design for a water sled, as shown and described.
